OIL BURNER CONTROL

Robert E. Fowler, Birmingham, Mich., assignor to
 General Motors Corporation, Detroit, Mich., a
 corporation of Delaware

Application December 12, 1936, Serial No. 115,512

2 Claims. (Cl. 158—28)

This invention relates to control devices and more particularly to control devices for liquid or gaseous fuel burners.

While the embodiment of this invention is illustrated and described as applied to an electrically operated liquid fuel heating system for domestic purposes, it will be understood that this invention may be used in other heating systems.

In the operation of a liquid or a gaseous fuel burner it is necessary to provide a means to prevent continued operation of the burner mechanism if it fails to generate heat at any time when the burner motor is on. In addition it is necessary to provide a means to ensure that should the current supply to the burner motor fail for any reason it will be impossible to start the motor without producing ignition for the fuel. Accordingly, it is the primary object of this invention to provide a simplified control means adapted to attain the results above mentioned.

A specific object of this invention is the provision of a simplified control means for a liquid or gaseous fuel burner involving a two way thermostatically operated switch and a relay utilizing two coils in different circuits and one in which the ignition means is controlled by means of a stack thermostat.

It is also an object of this invention to provide a simplified control circuit in which control thermostats are under lower operating voltages than is the control motor.

Other advantages and objects of this invention reside in the combinations and arrangement of parts as will become more apparent as the description proceeds. Reference is herein made to the drawing forming a portion of this specification, in which the figure is a schematic showing of one embodiment of my invention.

In the drawing M' represents a control motor adapted to supply the liquid fuel and air to the burner. The control motor is shown diagrammatically since the specific construction thereof forms no part of the present invention.

In the embodiment illustrated in the drawing the ignition is of the intermittently energized type, i. e., one which is not "on" at all times during operation of the motor. The burner motor M' and lead 4' are in parallel with the primary 2' of a transformer T', while the spark gap 8' is across the secondary 5' thereof. Leads 6', 7' complete the circuit which includes the primary 2'. A switch 9', which may be of the mercury type, is adapted to make and break the circuit which includes the transformer primary 2'. The switch 9' will preferably be located in such loca-

tion as to be actuated by the stack thermostat as it moves under the influence of the heat in the stack.

The motor circuit includes a lead 54', a normally closed switch S' operated by a relay 55', lead 56', warp switch 38', lead 3', the hold coil of relay 51', switch 77', leads 58' and 59' and the primary 14' of transformer T2'. The holding coil of relay 57' is of sufficient strength to hold the switch 77' in position but will not close the same. A stack thermostat 76' having contacts 44' and 46' completes the following circuit: Lead 60', contacts 26', 27', leads 61', 52', 63', 64', 65', 66', and the secondary 30' of transformer T2'. The circuit for operating relay 55' comprises the transformer secondary 30', lead 67', lead 68', contacts 24' and 26' and lead 60'.

When the room thermostat 25' requires heat the thermostat contacts will be closed by moving to the left as viewed in the figure. The stack temperature will be such that the stack thermostat switch contacts and switch 9' will be closed. Hence the circuit will be completed through the "close" coil of relay 57' and the motor M' will discharge a mixture of air and fuel into the furnace. Since switch 9' is now closed the ignition will be "on" and the mixture will be ignited. As the stack heats up the stack thermostat contacts will open and break the circuit and also open the ignition switch 9'. The motor will continue to operate, however, the hold coil of relay 57' being sufficient to maintain the motor circuit closed. This will continue until the room thermostat contact 26' is moved to the right to contact terminal 24'. The coil of relay 55' will then be energized to break the motor circuit at switch S'. This condition will be maintained until the room cools below the proper temperature whereupon the cycle of operation will be repeated.

The control means shown in the drawing comprises means to stop the control motor should the burner fail to supply heat for any reason. For example, should the supply of fuel fail, the room thermostat would continue to call for heat and hence the motor circuit across the line would be completed. The contacts 26', 27' of the room thermostat and the cold contacts 44', 46' of the stack thermostat would complete the circuit across the secondary of the transformer T2. The heating element 52' of the warp switch would begin to heat up. Since the stack would not be heated the contacts 44', 46' would remain closed and element 52' would become heated an amount sufficient to cause the bimetallic warp switch 38' 55

to open and break the motor circuit. The switch 38' will preferably be of such form as to demand a manual resetting.

- The stack thermostat also acts as a safety control upon a current failure. Should the current fail, switch 71' would immediately break the circuit to the motor since relay 51' would be de-energized. Before the motor circuit could be reestablished the close coil of the relay would have to be again energized and this could only take place by having the stack thermostat switch contacts be in contact and complete the circuit through the close coil. By the time the latter circuit would be reestablished switch 9' would also be actuated by the stack thermostat and would be in closed position to complete the ignition circuit. The time interval will, of course, be sufficient to allow purging of the furnace of any unburned combustible mixture.
- 20 In the circuit illustrated it will be noted that the several control thermostats are connected in the low voltage circuit across the secondary of the transformer T2'. This has the advantage that the circuits may be made and broken without sparking and are more sensitive. For these reasons, I prefer the thermostatic controls to operate under a lower voltage than does the burner motor. The burner motor will supply the power for operating some form of air pump and where liquid fuels are used preferably also provide a power means for an injector.

It will be seen that this invention comprises a simplified control means for automatic liquid or gaseous fuel burners having certain safety features to prevent operation of the burner motor under undesired conditions. The control circuits are such as not to readily get out of order and are such as to provide continuous service over long periods of time without attention.

40 It will be understood that various changes and modifications may be made in the circuits shown and described without departing from the spirit of my invention and I do not wish to limit the patent granted thereon other than as necessitated by the prior art.

I claim:

1. In a burner control; a power circuit which includes the primary of a transformer; a first relay; a second relay having a hold coil and a close coil; a burner motor and a circuit therefor connected in parallel with the transformer primary when the burner is in operation including a normally closed switch adapted to be opened by the first relay, a bimetallic switch and a third switch adapted to be moved into closing posi-

tion by the close coil of the second relay and held in closing position by the hold coil thereof, said hold coil forming a portion of said motor circuit and being connected in series therewith; an ignition means which includes a transformer connected in parallel with the motor; a circuit for said first relay which includes the secondary of said first mentioned transformer and a thermostatically controlled switch moved to closing position when a desired room temperature has been attained; a second circuit which includes the secondary of said first transformer, a switch operated by thermostatic conditions in the stack, the close coil of said second relay, a heating coil in proximity to the bimetallic switch and a switch moved to closing position when the room thermostat demands heat, said heating coil causing said bimetallic switch in the motor circuit to open should the stack thermostat not open after the burner motor has been operating for a desired time interval; and a switch actuated by the stack thermostat adapted to make and break the ignition circuit.

2. In a burner control system; a power circuit which includes the primary of a transformer; a first relay; a second relay having a close coil and a hold coil; a burner motor and circuit in parallel with the primary of the transformer during normal burner operation including a normally closed switch adapted to be opened by the first relay, a bimetallic switch and a third switch adapted to be closed by the close coil of said second relay and held in closed position by the hold coil of said second relay; a room thermostat having a cold position and a warm position; a stack thermostat; an ignition means including a transformer and circuit in parallel with the burner motor; a switch actuated by the stack thermostat adapted to make and break the ignition circuit; means for completing a circuit across the secondary of said first transformer when the room and stack thermostats call for heat including the close coil of said second relay and a heating coil in proximity to the bimetallic switch in the motor circuit, said heating coil being adapted to heat the bimetallic switch to break the motor burner circuit should the stack thermostat not become heated after a desired time interval; and means to complete a second circuit across the secondary of said first transformer when the room thermostat is in warm position including the coil of said first relay, whereby said normally closed switch in the burner motor circuit is opened.
